INVENTOR

BY

John P. Mikonow
ATTORNEY

UNITED STATES PATENT OFFICE.

MICHAEL S. MASTRUKOFF, OF NEW YORK, N. Y.

PALETTE.

Application filed January 6, 1925. Serial No. 801.

To all whom it may concern:

Be it known that I, MICHAEL S. MASTRUKOFF, citizen of Russia, and resident of New York city, in the county of New York 5 and State of New York, have invented certain new and useful Improvements in Palettes, of which the following is a specification.

My invention relates to palettes or shallow trays used by the artists in mixing colors and paints, and has a particular reference to palettes used in mixing water colors.

The object of my invention is to provide a palette especially suitable for the use of thin and wide brushes or, more particularly, for the use of my new and improved method in applying water colors by means of wide strips of cardboard.

My invention is more fully described in the accompanying specification and drawing in which—

Fig. 1 is a plan or top view of my palette, Fig. 2 is a section on the line 2—2, Fig. 3 is a longitudinal section on the line 3—3, 25 and Fig. 4 is a longitudinal section of a palette made of glass or porcelain.

My palette consists of a flat piece of metal or similar material 1, formed with long and narrow troughs or grooves 2. These grooves or depressions are arranged in substantially parallel directions and preferably in straight lines. The walls of these depressions are made preferably flat and at an angle with the upper surface of the palette, converging 35 at the bottom of the grooves so as to form sharp pointed wells or containers for the liquid paints or colors.

With this arrangement it is possible to extract the liquid from the grooves practically up to the last drop, using thin and wide brush or a piece of cardboard as a brush 40 (as I recommend to use with my new method

of applying water colors), at the same time providing an uniform covering of the brush or cardboard with the color throughout full 45 width of this brush.

The edges 3 of the palette are bent down all around so as to form an uniform and even edge 4 at the bottom for the palette to rest on the flat surface of a table. The 50 edges, bent all around as shown, add greatly to the appearance of the palette, so that such a palette, made of a thin metal and properly enameled, may have the appearance of an article made of porcelain. 55

Of course, my palette may be made of any suitable material, and Fig. 4 shows such a palette made of glass or porcelain.

The walls of the grooves may be also curved, but any such curvature must be only in a 60 cross section, as longitudinally the walls and the grooves should be arranged along straight lines in order to facilitate the use of flat brushes, as mentioned above.

My palette has special and important advantages over ordinary palettes, when used in connection with my method of applying colors with a thin wide brush or a cardboard, as it gives an uniform distribution of coloring material throughout the full 65 70 width of the brush.

I claim as my invention:

A palette of a substantially elongated rectangular form and provided with a plurality of parallel grooves extending lengthwise 75 through said palette and terminating near its ends, each of said grooves forming a long and narrow trough from one end of said palette to the other and adapted to contain a coloring liquid. 80

Signed at New York in the county of New York and State of New York January A. D. 1925.

MICHAEL S. MASTRUKOFF.
